Patented Mar. 14, 1916.

Inventor,
Theodor Qviller
By Henry Orth Batt.

UNITED STATES PATENT OFFICE.

THEODOR QVILLER, OF LILLESTRÖMMEN, NEAR CHRISTIANIA, NORWAY.

PULSATING SCREEN FOR PULP AND THE LIKE.

1,175,293.

Specification of Letters Patent. Patented Mar. 14, 1916.

Application filed August 4, 1915. Serial No. 43,619.

To all whom it may concern:

Be it known that I, THEODOR QVILLER, a subject of the King of Norway, residing at Lillestrømmen, near Christiania, Norway, have invented certain new and useful Improvements in Pulsating Screens for Pulp and the like; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

My present invention relates to improvements in pulsating screens for pulp and the like particularly of the type described in my prior Letters Patent No. 1124802.

The chief object of my invention is to provide a pulsating screen of the kind referred to with means for removing coarse particles and waste accumulating on the screen cylinder so that said coarse particles will not obstruct the slots in the screening cylinder and prevent the same from acting on the fresh pulp fed into the apparatus.

The invention also has for its object to simplify the construction of the apparatus shown in my said prior patent.

In the accompanying drawings: Figure 1 is a section on the line *a*, *a* of Fig. 2. Fig. 2 is an axial vertical section of the screening apparatus. Fig. 3 is an end view of the same. Fig. 4 is a cross section through the screening cylinder and the interior parts of the apparatus on the line *b*, *b* of Fig. 2. Fig. 5 is a vertical axial section on a larger scale through one end of the apparatus illustrating the packing for the screening cylinder.

2 designates a screen which is formed as a cylinder and is almost completely submerged in the pulp which is introduced at 1 so that only a small part of the screen projects above the pulp. Inside the screening cylinder two other rotating cylinders 4, are mounted on the same shaft with a short space between their adjacent ends, in which space there are placed guide vanes 17. A plurality of chambers 3 are formed, between the cylinder 2 and the cylinders 4, by longitudinal radial ribs 9 on the inner periphery of the cylinder 2. Openings 21 are provided in the end walls of cylinders 4 adjacent to the guide vanes 17 so that the pulp can pass

into the cylinders 4 between the guide vanes 17 and through the said openings 21. The rotating cylinders 4 are provided with peripheral openings 22 and with internal 60 radial pump blades 16 for causing the pulp to be driven out of said openings 22 by means of centrifugal force. In this way pressure is produced in the chambers 3 between the inner surface of the screening cylinder 2 and the rotating cylinders 4. Suction is produced in the chambers 3 by means of the suction openings 21, which are brought to register with said chambers 3 after the pressure opening 22 has passed the same 70 (see Figs. 1 and 4). It will be noted that the rotating cylinders 4 act in the same manner as the cylinder D shown in my prior Letters Patent No. 1124802, the difference lying in the feature that the cylinders 4 act 75 as pumps, while in my Patent No. 1124802 a separate pump had to be provided for producing suction and pressure in the screening chambers. The opposite walls of the cylinders 4 are provided with covering 80 plates 5 having openings 10 for letting out the screened pulp from the apparatus. The said covering plates may preferably be adjustable so as to permit a regulation of the openings 10. An outlet 18 (see Fig. 3) is 85 provided for letting out the screened pulp from the end chambers.

The receptacle inclosing the screening cylinder is provided with removal side covers 19, 20, and its bottom has openings 30, by 90 means of which it communicates with the tubular chamber 31 provided with the outlet 11, which may be adapted to be closed by means of a valve or the like. The end covers 15 of the receptacle inclosing the screening cylinders are provided with cleaning 95 openings, which are normally kept closed by means of covers 25.

The screening cylinder is provided on its outer periphery with angular longitudinal 100 ribs 12, and the cylinder ends are provided with radial flanges 13, having openings 8 in front of each rib 12. Packing ribbons 23 are provided between the stationary receptacle end walls and the ends of the screening 105 cylinder.

The screening cylinder is provided with cylindrical extensions 14 by means of which it is rotatably mounted as shown on Fig. 2 on inwardly projecting circular flanges 32 110 on the end covers 15.

The screening cylinder may be rotated in

any convenient manner, but preferably as shown on Fig. 3 by means of an eccentric 29 on a shaft 33 and actuating pawl 27 so as to drive a ratchet wheel 34 connected with 5 said cylinder.

The mounting of the screening cylinder on the flanges 32 is shown on a larger scale in Fig. 5. An annular channel 35 is covered on its outside by a rubber ring 36, which 10 may be fastened by means of copper wire or the like 37 and is inclosed by a leather ring 38, also fastened by means of copper wire 39 on one side. Water under pressure is led into the annular channel 35 through 15 the tube 40, so that pressure is produced in the same, and the leather ring 38 is pressed against the inside of the extension 14. There is also provided an outlet 41 from the 20 annular chamber 35, and the pressure in said chamber may be regulated by means of cocks or valves in the inlet and outlet.

The operation of the apparatus is substantially the same as of the apparatus described in my prior Patent No. 1124802. 25 The mass let in at 1 passes downwardly along one side of the screening cylinder. While the fine particles are sucked through the screen, the coarse particles will be taken up by the ribs 12 to the part of the screening 30 cylinder projecting above the pulp mass, and at this point the said particles are subjected to the action of a shower pipe 26 which acts to drive the said particles through the openings 8 in the flanges 13 to 35 outlets 7, non-return clappers 28 or the like being provided in front of the said outlets 7 in order to prevent the coarse particles from returning into the screening receptacle.

As the ribs 12 for practical reasons can 40 not be made to cover the whole space between the screening cylinder and the receptacle some coarse particles will always be left at the bottom of the receptacle, and said particles are let out through the outlet 11. 45 All the coarse particles ejected from the

apparatus are led to an auxiliary screening chamber, where the waste is expelled, while the finer particles are brought back to the screening cylinder. Said auxiliary chamber may be of the same kind as the chamber F 50 shown in my Patent No. 1124802 but it may also be formed otherwise if so is desired.

I claim:

1. In pulsating screens for pulp and the like a screening cylinder, means for imparting a slow rotative movement to the same, longitudinal ribs outside said cylinder, longitudinal radial ribs inside said cylinder dividing the latter into several sections, and a rotating member adapted to expose the 55 several sections of the screen alternately to the action of pressure and suction channels.

2. In pulsating screens for pulp and the like a rotating screening cylinder, longitudinal radial ribs inside said cylinder 60 dividing the latter into several chambers, two rotating cylinders mounted inside and coaxially with the same, and having inlet openings at their adjacent ends, pump blades between the radial ribs inside the cylinders, 65 said screening cylinder having rows of outlet openings intermediate said ribs.

3. In pulsating screens for pulp and the like a receptacle for pulp mass, a rotating screening cylinder inside said receptacle and 70 almost submerged in the pulp, longitudinal ribs outside the screening cylinder for taking with them coarse particles, flanges at the ends of said screening cylinder having openings adjacent to said ribs, and a shower pipe 75 above the screening cylinder for ejecting the coarse particles from the same.

In testimony that I claim the foregoing as my invention, I have signed my name in presence of two subscribing witnesses.

THEODOR QVILLER.

Witnesses:
